WALL-HEATER CABINET

Juan Alfonso Fellner, Cordoba 632,
Buenos Aires, Argentina

Filed Dec. 14, 1961, Ser. No. 67,915

Term of patent 7 years

(Cl. D81—10)

The FIGURE is a perspective view of a wall-heater cabinet showing my new design.

The opposite side of the wall-heater cabinet is similar to the one which is shown, while the top, rear and bottom of wall-heater cabinet consist of flat surfaces.

I claim:

The ornamental design for a wall-heater cabinet, as shown and described.
